UNDERWATER SUCTION ANCHORS

Virgil E. Johnson, Jr., Gaithersburg, and William C. Webster, Brookville, Md., assignors to Hydronautics, Inc., Laurel, Md., a corporation of Maryland
Filed Feb. 18, 1966, Ser. No. 528,635
10 Claims. (Cl. 114—206)

ABSTRACT OF THE DISCLOSURE

A self-propelled maneuverable anchor of ogive configuration including a water-tight chamber with a motor therein and an impeller chamber forward of the motor chamber, the housing having a centrally disposed pump inlet to the impeller chamber and rearwardly oriented water outlets therefrom with a sealing means thereon concentric with the inlet. The rearward end of the housing, adjacent the apex of the ogive, has vanes extending radially therefrom for guiding the anchor through the water, the vanes being adjustable to maneuver the anchor, or when not adjustable, maneuverability being accomplished by varying the discharge of the water from the impeller chamber outlets.

This invention relates generally to anchors and more particularly to maneuverable anchors which are attached to submerged objects.

Devices of the general class to which this invention pertains are used for marking, attaching to, retrieving or otherwise operating on submerged objects or formations. These devices generally include an attaching means, usually a suction apparatus to attach the device by hydrostatic pressure differential, and a system for lowering the attaching means into a body of water. In the prior art, the suction power for the attaching means has generally been applied from a shipboard or surface pump through a hose associated with the lowering system.

This invention relates to improvements in the above described art and it is an object of this invention to furnish an anchor of the type described which has a capability for maneuvering by utilizing the suction producing source thereof as a means to maneuver and/or propel the anchor.

It is another object of this invention to furnish a self-propelled suction anchor which requires a minimum of surface connecting structure by providing a self-contained source to furnish both suction and propulsion for the anchor.

It is a further object of this invention to furnish a self-propelled anchor which is guidable from a surface location by providing remotely controlled maneuvering means for the anchor.

It is still another object of this invention to furnish a suspension system for a suction anchor which imposes a minimum parting moment to the anchor by gimbaling the support proximate the attaching point thereof.

These and other objects of the invention will become better understood to those skilled in the art by reference to the following detailed description when viewed in light of the accompanying drawings wherein like numerals indicate like parts throughout the figures thereof and wherein:

FIGURE 1 is a sectional view of an anchor embodying features in accordance with the invention.

FIGURE 2 is a diagrammatical view showing the operation of a device in accordance with the invention for application to the hull of a submerged vessel.

FIGURE 3 is a view similar to FIGURE 1 of a modified form of the invention.

Turning now to FIGURE 1 for a more detailed description of the device, the anchor comprises a housing

2

10 which encloses a motor 12 in a watertight chamber between bulkheads 14 and 16. The motor 12 is connected to a centrifugal pump impeller 18, disposed in an impeller housing 20 in a forward portion of the device, through a pump shaft 22 rotatably mounted in a bearing 24 disposed in the bulkhead 16. The impeller housing is provided with a pump inlet 26 concentrically disposed in a transverse forward wall and rearwardly oriented pump outlets 28 disposed equidistantly around the periphery thereof. An annular elastomeric seal 30 is concentrically disposed on the forward wall of the housing 10 around the pump inlet 26 and serves to provide a suction attaching means for the anchor.

15 A supporting bale 32 is gimballed to the housing 10 proximate the suction attaching means through bearings 34. This bale serves to provide support and a pivotal connection to a support cable 36 through an eye 38 on the end thereof. Insulated electrical cable 40 extends from the support cable 36 to provide power for the motor 12 through a power conductor 41 and for other purposes to be described below.

20 Radially disposed vanes 42, pivotally mounted on a ball joint 44, through openings 48 in the housing 10 are encompassed by an annular shroud 46 to form a tail vane assembly. An electrically powered actuator 50 is mounted on the bulkhead 14 and is connected to the vanes 42 to provide means to change the orientation of the vanes and shroud with respect to the housing 10 for purposes to be described below. Power is supplied to the actuator 50 through a control conductor 52 which, combined with the electrical cable 40, is attached to the support cable 36 and connected to a control source (not shown) on the ship from which the anchor has been launched.

25 35 The rear portion of the housing 10 is configured in the form of a rearwardly tapering ogive having a decreasing diameter, behind the pump outlets 28, of sufficient magnitude to build up a large fluid boundary layer in this area to increase the effectiveness of the propulsion means as will be explained later.

30 In FIGURE 2, the anchor 8 is suspended through the cable 36 from a mother ship 54 and, under power, is controlled from a mother ship toward the hull of a submerged vessel 56. The anchor 8 is shown in contact with the surface of a submerged vessel 56 in phantom lines.

45 In the operation of the device of the figure, the anchor is lowered into the water from a mother ship 54 (FIGURE 2) and the motor 12 is energized to start the action of the pump impeller 18. Water drawn in through the inlet 26 is expelled through the outlets 28 in the form of high velocity jets directed into the above-mentioned large fluid boundary layer on the rear portion of the housing 10.

50 55 The boundary layer, moving at a velocity substantially lower than that of free stream water increases the effectiveness of the jets from the outlets 28 in propelling the anchor through the water. The anchor 8, propelled through the water by the jets, is maneuvered by change in orientation of the tail vane assembly by energizing the actuator 50 as required.

60 65 When the seal 30 makes contact with a smooth surface, such for example as the submerged ship 56 (FIGURE 2), the pump, in withdrawing water through the intake 26, creates a low pressure region within the space defined by the seal 30 and the pressure difference between this region and the water surrounding the anchor holds the anchor firmly on the surface. Small leakages due to surface irregularities and the like will not diminish the holding force since the pump will be continuously operating to withdraw water caused by such leaks from the low pressure area. The arrangement of the gimballed connection

for the bale 32 nad the disposition of the connection between the bale and the housing 10 provides a minimum moment for any forces acting through the cable 36 which would tend to pry the anchor off of the surface to which it is attached.

In FIGURE 3, a variation of the embodiment of FIGURE 1 is shown and the components thereof corresponding to equivalent components in the embodiment of FIGURE 1 are indicated by like numerals only of the next higher order. The primary distinction between the version of FIGURE 3 and that of the preceding figure lies in the apparatus for controlling the orientation of the housing or guiding the anchor through the water. In the version of FIGURE 3, the vanes 142 and the shroud 146 are fixed to the housing 110. A valve 160, operated by a solenoid 162 mounted on the bulkhead 116, is provided over each of the pump outlets 128 to control the effluent therefrom. Each of the solenoids 162 is controlled through an electrical conductor 164 which ties in with the conductor cable 140 and extends up to the mother ship 54 (FIGURE 2) with the cable 136.

By selective operation of the solenoids 162, the effluent through the outlets 128 can be controlled as desired to thereby guide the anchor in its passage through the water. By shutting off one or more of the outlets 128, the unbalanced forces imposed on the anchor will cause it to turn in the direction of the closed outlets thereby providing means to alter the orientation of the anchor. The operation of the remaining components of the anchor of FIGURE 3 is identical to that of the corresponding components of FIGURE 1 as described above.

What has been set forth above is intended as exemplary of teachings in accordance with this invention to enable those skilled in the art in the practice thereof. It should therefore be understood that, within the scope of the appended claims, the invention may be practiced otherwise than as specifically described.

We claim:

1. A self-propelled maneuverable anchor for suction attachment to submerged surfaces comprising: a pump means including a housing; a pump inlet and at least one outlet through said housing, said outlet configured to direct the effluent from said pump along said housing to propel the anchor through water; an annular seal disposed around said pump inlet; a support means connected to said housing for lowering the anchor into a body of water; and adjustable means to controllably guide the anchor through water.

2. A maneuverable anchor for suction attachment to submerged surfaces comprising: a pump means including a housing; a pump inlet and at least one outlet through said housing, said outlet configured to direct the effluent from said pump along said housing to propel the anchor through water; an annular seal disposed around said pump inlet; a support means connected to said housing for lowering the anchor into a body of water; means to controllably guide the anchor through water, and wherein a plurality of outlets are provided in said housing and wherein said means to controllably guide the anchor through water comprises:

a valve associated with each of said outlets to independently control the effluent therefrom to alter the orientation of said housing when said anchor is moving through water.

3. A maneuverable anchor for suction attachment to submerged surfaces comprising: a pump means including a housing; a pump inlet and at least one outlet through said housing, said outlet configured to direct the effluent from said pump along said housing to propel the anchor through water; an annular seal disposed around said pump inlet; a support means connected to said housing for lowering the anchor into a body of water; means to controllably guide the anchor through water, and wherein radially extending vanes are pivotally mounted on said housing and wherein said means to controllably guide the anchor through water comprises:

at least one actuator connected between said vanes and said housing to change the orientation therebetween to alter the orientation of said housing when said anchor is moving through water.

5. A maneuverable anchor for suction attachment to submerged surfaces comprising: a pump means including a housing; a pump inlet and at least one outlet through said housing, said outlet configured to direct the effluent from said pump along said housing to propel the anchor through water; an annular seal disposed around said pump inlet; a support means connected to said housing for lowering the anchor into a body of water; means to controllably guide the anchor through water, and wherein said support means includes a bale pivotally connected to either side of said housing proximate said pump inlet; whereby said housing is movable relative to the supporting means.

5. A maneuverable anchor for suction attachment to submerged surfaces comprising: a pump means including a housing; a pump inlet and at least one outlet through said housing, said outlet configured to direct the effluent from said pump along said housing to propel the anchor through water; an annular seal disposed around said pump inlet; a support means connected to said housing for lowering the anchor into a body of water; means to controllably guide the anchor through water, and wherein said housing includes a front portion having a substantially flat transverse forward wall and a rearwardly tapering rear portion having vanes adjacent the end of the rearwardly tapering portion of said housing, said vanes having their inner ends mounted on the housing and extending radially out from the housing.

6. A maneuverable anchor for suction attachment to submerged surfaces comprising: a pump means including a housing; a pump inlet and at least one outlet through said housing, said outlet configured to direct the effluent from said pump along said housing to propel the anchor through water; an annular seal disposed around said pump inlet; a support means connected to said housing for lowering the anchor into a body of water; means to controllably guide the anchor through water, said housing including a front portion having a substantially flat transverse forward wall and a rearwardly tapering rear portion having a radially extending vane mounted thereon, and wherein said inlet is centrally disposed in said forward wall and said outlets are rearwardly oriented and disposed through the periphery of said housing.

7. An anchor in accordance with claim 6 wherein said support means includes a bale pivotally connected to either side of said housing proximate said forward wall.

8. An anchor in accordance with claim 7 wherein a plurality of outlets are provided in said housing and wherein said means to controllably guide the anchor through water comprises:

a valve associated with each of said outlets to independently control the effluent therefrom to alter the orientation of said housing when said anchor is moving through water.

9. An anchor in accordance with claim 7 wherein said vanes are pivotally mounted on said housing and wherein said means to controllably guide the anchor through water comprises:

at least one actuator connected between said vanes and said housing to change the orientation therebetween to alter the orientation of said housing when said anchor is moving through water.

10. A self-propelled maneuverable anchor having an ogive configuration for suction attachment to a submerged surface including:

said housing having a rearward water-tight motor chamber and an impeller chamber forward of the motor chamber,

motor means within the motor chamber having a drive shaft extending into the impeller chamber,

an impeller on said shaft,

the impeller chamber being provided with a centrally

- located water inlet and rearwardly disposed water outlets,
a sealing means secured to the forward end of the impeller chamber and concentric with the centrally disposed water inlet,
a vane means securely mounted on the housing at the apex of the ogive and extending outwardly from the housing, and
adjustable means to controllably guide the anchor through the water.
